[57] CLAIM

The ornamental design for a mini car vacuum cleaner,
as shown and described.

DESCRIPTION

FIG. 1 is a top plan view of a mini car vacuum cleaner
showing my new design;

FIG. 2 is a right side elevational view thereof, the oppo-
site side being a mirror image;

FIG. 3 is a bottom plan view thereof;

FIG. 4 is a front elevational view thereof;

FIG. 5 is a rear elevational view thereof; and

FIG. 6 is a top, front and side perspective view thereof.
